ACOUSTICAL MINE FIRING CONTROL SYSTEM
Grant N. Willis, Washington, D.C.
Filed Jan. 19, 1945, Ser. No. 573,621
13 Claims. (Cl. 102—18)
(Granted under Title 35, U.S. Code (1952), sec. 266)

This invention relates to mine firing control systems and more particularly to an acoustic mine firing control system for underwater mines wherein the system operates to detonate and explode the mine associated therewith when vibrations or pulsations of a predetermined character are transmitted through the surrounding water from sound emitting bodies such as surface vessels, submarines, or the like, and the system operates to prevent a firing of the mine when heavy explosive charges, such as those employed in countermine operations, are exploded within the vicinity thereof.

In certain of the prior art systems, electric contact actuating apparatus comprising a plurality of contacts is employed wherein a first pair of the contacts is adapted to be actuated by sound waves or pulses of predetermined character such, for example, as those produced by a vessel, thereby to control the operation of a mine firing circuit, and a second pair of the contacts is adapted to be actuated by sound waves or pulses of different character such, for example, as explosion waves, thereby to prevent the first pair of contacts from controlling the firing circuit when such different sound waves or signals are received. Thus, by this arrangement, a certain measure of protection or discrimination against such sound waves or signals is provided. In accordance with such an arrangement, a time delay device is usually employed to continue the control provided by the second pair of contacts for a predetermined interval of time, thereby to render the firing circuit inoperative until the aforesaid different signals have died out in the acoustic field or zone of receptivity of the mine.

In certain of the other prior art systems, microtelephonic devices are employed to initiate the operation of intermediate devices adapted gradually to close a mine firing circuit in response to signals received from a vessel adapted to be destroyed by the mine employing the system. By reason of the gradual action in closing the mine firing circuit, the system is caused to begin its operation while the vessel is at a relatively great distance from the mine, thereby to fire the mine only after a period of time sufficient to bring the vessel close enough to the mine to destroy or effectively damage the vessel. Such an arrangement affords a further advantage in that it precludes a firing of the mine by the explosion of shells or bombs in its vicinity, sound waves or pulses caused by such explosions being momentary only and therefore too brief to effect a firing actuation of the system.

In the arrangement of the present invention, an acoustic mine firing control system is provided which possesses all of the advantages of the prior art systems and in addition provides a system wherein certain circuit elements are chosen and arranged in such manner as to provide a relatively high degree of control of the operation of the system in response to signals of predetermined character received thereby from vessels moving with respect thereto whereby the mine is fired beneath a vulnerable portion of the vessels substantially independently of the speed of the vessels, and the system provides a higher degree of anti-countermine protection than that afforded by the prior art systems.

In accordance with the present arrangement, a sound responsive device is employed, which device comprises a pair of contacts adapted to be actuated by vibrations or

2

pulsations of predetermined character and thereby cause the vibrations or pulsations to be converted into electrical signals corresponding thereto. A condenser is connected to the control element of a trigger type tube and is adapted to be charged by the electrical signals, whereby the tube is caused to break down and effect the discharge of a normally charged condenser through a shipcounter or an electro responsive detonating device, as the case may be. A second pair of contacts on the sound responsive device are adapted to be closed in response to a countermine shock received thereby, whereupon a second trigger type tube is caused to break down and effect a discharge of the normally charged condenser therethrough, thus sterilizing the system for a predetermined period of time corresponding to the time required to recharge the normally charged condenser.

According to the mine firing control system of the instant invention, the elements or component parts thereof comprise static or non-moving parts such, for example, as condensers, resistors and electron discharge devices, which elements are not susceptible to damage caused by shocks associated with the launching of a mine. Accordingly the system of the present invention is well adapted for use in connection with mines adapted to be planted from an aircraft in flight.

An object of this invention is to provide a new and improved acoustic mine firing control system which operates in response to signals of a predetermined character to actuate a mine firing control circuit and operates in response to signals of a different character to prevent the operation of such a circuit.

Another of the objects is the provision of a new and improved acoustic mine firing control system for a marine mine adapted to fire the mine when a predetermined number of series of vibrational signals has been received through the surrounding water corresponding to the movement of a predetermined number of vessels past the mine.

Another object is the provision of a new and improved acoustic mine firing control system for an underwater ground mine in which means are provided for effecting a predetermined number of counting operations, corresponding to a predetermined number of vessels moving past the mine, which operations are substantially independent of the time of travel of each of the vessels past the mine.

Another object in an acoustic mine firing control system is the provision of new and improved means responsive to countermine shocks and adapted to sterilize the system for a predetermined period of time.

Another object is the provision of a new and improved acoustic mine firing control system in which the firing of the mine in response to sound signals of a predetermined character received thereby is delayed for a predetermined period of time.

Another object is the provision of a new and improved acoustic mine firing control system which operates in response to signals of a predetermined character to actuate a mine firing control circuit and which provides means for preventing an actuation of the mine firing control circuit when signals of a predetermined character and of a different character are received concurrently thereby.

Still another object of this invention is to provide an acoustic mine firing control system for a marine mine in which the system operates to produce a firing actuation thereof only in response to signal frequencies which are within a predetermined frequency band.

Still another object of this invention is to provide a new and improved acoustic mine firing control system for a marine mine in which the system operates to produce

a firing actuation thereof only in response to signals which reach a predetermined degree of strength.

A further object is the provision of an acoustic mine firing control system for a marine mine in which an energy storing device is caused to discharge through a shipcounting device in response to vibrational signals transmitted through the surrounding water by a vessel moving past the mine and in which means are provided for causing the condenser to charge and discharge repeatedly during the travel of the ship past the mine without additionally operating the shipcounter.

A still further object is the provision of an acoustic mine firing control system which is rugged in construction, economical to manufacture and reliable in service.

Additional objects and advantages, not specifically set forth heretofore, are implied or are inherent in the novel construction, combination and arrangement of the elements comprising the invention and will become more clearly apparent as the description proceeds, reference being had to the accompanying drawings wherein:

FIG. 1 is a sectional view with certain parts in elevation of an underwater ground mine suitable for use with the instant invention;

FIG. 2 is a sectional view of the device of the present invention;

FIG. 3 is a view, partially broken away and partially in section, taken substantially along the line 3-3 of FIG. 2;

FIG. 4 is a view, partially broken away and partially in section, taken substantially along the line 4-4 of FIG. 3;

FIG. 5 is a view in section taken substantially along the line 5-5 of FIG. 4;

FIG. 6 is a view, partially broken away and partially in section, taken substantially along the line 6-6 of FIG. 4;

FIG. 7 is a sectional view taken substantially along the line 7-7 of FIG. 4; and

FIG. 8 shows in diagrammatic form a complete system suitable for use with the mine of FIG. 1.

Referring now to the drawings for a more complete understanding of the invention, wherein like reference characters refer to like parts throughout the several views, and more particularly to FIG. 1 thereof, the numeral 10 generally designates an underwater mine adapted to be planted from an aircraft in flight and adapted to come to rest on the bed of a body of water in which the mine is planted. The mine comprises an outer casing 11 generally of cylindrical configuration and having a reduced end portion to which fins 12 or the like are secured to steer or guide the mine in flight.

The casing 11 is divided internally at the reduced end portion thereof by a bulkhead 13 which supports a well 14 for a purpose hereinafter disclosed. The casing 11 is also provided with inwardly extending wells 15 and 16 from which extend respectively, tubes or ducts 17 and 18 to the bulkhead 13. The casing is further provided with a well 19 in which a percussion detonator may be inserted, if desired, when the mine 10 is to be used for purposes other than those disclosed herein. Accordingly, for purposes herein disclosed, the well 19 is sealed as by the plug 21.

The remaining space within the main portion of the casing 11 is filled with an explosive charge 22 of TNT or the like sufficient to destroy or damage a vessel and to impart a negative degree of buoyancy to the mine whereby the mine is caused to sink through the water and come to rest on the bed thereof. The explosive charge conveniently may be admitted into the casing by way of a suitable watertight filler opening 23.

A booster charge 24 and the extender mechanism 25 usually associated therewith are arranged within the well 15 in water-tight relation therein. The extender mechanism carries an electro-responsive detonator 26 for igniting the booster charge 24 and is adapted to move the

detonator into operative engagement with the booster charge when the mine reaches a predetermined depth of submergence in the water, as is well known in the art to which the invention appertains. The leads 27 of the detonator comprise a cable 28, which is extended through the duct 17 to the reduced end portion of the casing 11.

Arranged within the well 16 in watertight relation therewith, is a clock mechanism 29 adapted to complete certain circuits of the electrical system within predetermined intervals of time after the mine has been launched within the water, as will more clearly appear as the description proceeds. For this purpose, a multi-conductor cable 31 connected to contacts comprising the clock mechanism is extended through the duct 18 into the reduced end portion of the casing.

The well 14 serves as a housing and support for a battery, hereinafter referred to as BA, the battery being clamped within the housing against a resilient support 32 therein by means of a retaining ring 33 secured to the bulkhead as by a plurality of studs 34. The battery BA is arranged to supply electrical energy to a firing control mechanism 35 by way of a multi-conductor cable 36 when the aforesaid certain circuits have been closed by the clock mechanism 29 as explained in the foregoing.

The mechanism 35 is supported on the studs 34 by means of a plurality of flexible spacer plates 37, which plates may be formed of any suitable material such, for example, as wood, the plates being supported on the studs and shaped to conform to the end portions of the mechanism. The free end portions of the studs 35 extend through and are supported by the plate 38, which plate is shaped to conform slideably with the inner surface of the casing 11. The projecting portions of the studs are threaded to receive a plurality of nuts 39 whereby the mechanism 35 may be clamped between the plates 37 when the nuts are drawn up tight against the slideable plate 38, substantially as shown.

The reduced end portion of the mine casing, at the open end thereof, carries a ring member 41 which is secured to the casing as by welding or otherwise suitably secured thereto. A dish-shaped cover 42 is secured to the member 41 in watertight relation therewith as by a plurality of screws 43 carried by the flange portion 44 of the cover. The cover is provided with a central opening for receiving a sound responsive device 46 herein after referred to as an acoustic tickler. The device 46 is provided with a circular base 47 by means of which the device is secured, as by a plurality of screws 48, to the cover, a suitable gasket 49 being inserted between the cover and the base to insure a watertight connection therebetween.

The sound responsive device or tickler 46 is shown in greater detail in FIGS. 2 through 7, the device comprising a support 51 secured to a circular base 47 as by a plurality of screws 52. Also secured to the base 47 is a casing 53 for the device, which casing is provided with a circular flanged portion 54 having a plurality of holes therein adapted to receive the screws 48. A thin flexible diaphragm 56, preferably circular in shape and of a material suitable for the purpose such, for example, as beryllium copper or sheet metal, is mounted between the base 47 and the supporting member 51. The base 47 is provided with a recessed aperture 55 which allows pulsations or vibrations received through an elastic medium to react upon the surface of the diaphragm.

The diaphragm 56 and support 51 are provided with coincident apertures within which is disposed a post 57 securely clamped to the diaphragm by means of a packing nut 58 screwed to a threaded extremity of the post 57 whereby oscillation of the diaphragm causes the post to oscillate. A suitable gasket 59 is arranged between the packing nut and diaphragm to insure a watertight relation therebetween.

Secured to the supporting member 51 by means of the screws 64 are the mounting strips 61, 62 and 63, each

being electrically insulated from the other by a strip of suitable insulating material 65 such, for example, as rubber, Bakelite or the like, the strip 63 also being insulated from the support 51 by an additional strip of similar insulating material. The mounting strip 63 has two upright portions 66 and 67, the portion 66 having a threaded hole therein adapted to receive the adjustable screw bearing 68, the portion 67 also being provided with a threaded hole therein adapted to receive the screw bearing 69. A nut 71 is provided upon the bearing 69 for maintaining the bearing in an adjusted position with respect to the upright portion 67. Disposed about the adjustable screw bearing 68 is an internally bored circular member 72 and releasably clamped between the member 72 and support 66 by the screws 79 is another circular member 81 having a relatively large inside diameter. Extending from the member 81 is an arm 73 which may be moved to any desired setting by loosening the screws 79 and rotating the member 81. Secured to the arm 73 is a resilient spring 74 known in the trade as a hair spring, having the other end thereof in engagement with the shaft 75. The screw 68 is provided with a tapped hole concentric with the axis of the screws 68 and 69 by means of which the shaft 75 is mounted for rotation about the axis. The balance wheel 76 is secured to the shaft 75 and rotatable therewith, the balance wheel being provided with an electrical contact 77 adapted to engage contact 78 affixed to the post 57 and be stopped thereby when the device is in a state of rest, the pressure between the contacts 77 and 78 being maintained at a predetermined value by the tension of the hair spring 74 in accordance with the setting of the member 81.

The mounting strip 62 has an electrical contact 82 extending therefrom adapted to be engaged by the contact 77 affixed to the balance wheel when the pressure signal acting upon the diaphragm 56 is of sufficient magnitude. The conductor 83 is soldered to the post 57 thereby maintaining the conductor in electrical connection with contact 78. Similarly, conductor 84 is soldered to the mounting strip 61, thereby maintaining conductor 84 in electrical connection with contact 77; while conductor 85 is fixed to the mounting strip 62 thus maintaining conductor 85 in electrical connection with contact 82.

A suitable cup-shaped cover 86 is secured to the support 51 by a plurality of screws 87, the cover having arranged therein a partition 88 with a flanged portion 89 provided with a hole which is adapted to receive the post 57. In the bottom of the cover are a plurality of holes through which the conductors 83, 84 and 85 are passed, with encasing means 91 being provided for each conductor to prevent water from seeping into the cover. A suitable gasket 92 is mounted between the cover 86 and support 51, thereby insuring a watertight connection therebetween.

The device is also provided with a rubber sack 93 arranged within the casing 53, the sack being securely clamped between the base 47 and the flange portion 54. Cut into the flanged portion 54 is a port 94 which allows water to pass into the space between the casing 53 and the sack 93, thereby deflating the sack and causing the air therein to be compressed. A hole 95 in the cover 86 also allows the air within the cover to be compressed and by reason of a plurality of holes 135 cut in the support 51, the resulting air pressure is applied to the surface of the diaphragm 56 against the support, thereby substantially equalizing the total pressure applied to the diaphragm when the device is immersed in a body of water.

A housing 96 is secured to the casing 53, the housing having holes cut in its top and bottom surfaces through which the cable 97, containing conductors 83, 84 and 85, is passed. A plurality of holes are also cut in the casing 53 to allow passage therethrough of the conductors 83, 84 and 85, with suitable encasing means being provided at each hole in the casing 53 and housing 96 to

prevent leakage of water into the device 46 and also to prevent air from escaping the device.

A short description of the operation of the sound responsive device 46 will now be given. Let it be assumed by way of example that the mine 10 has been launched in a body of water and has come to rest on the bed thereof, its position being adjacent the path of travel of an approaching vessel and that the mine is in an armed condition. The diaphragm 56 is now subject to the pressure of the surrounding water and in order to compensate for this, water flows into the port 94, thereby causing the rubber sack 93 to partially collapse. When this occurs, air contained in the casing 53 and in the cover 56 is compressed sufficiently to substantially equalize the pressure acting on the surface of the diaphragm which is in contact with the surrounding water.

As is well known in the art to which the invention appertains, it has been found that a considerable range of frequencies is transmitted by the propeller of a ship in motion. The system of the present invention has been designed to operate on a frequency band included within the sonic range of frequencies generated by the ship's propeller.

The sound intensity received through the water is of a relatively small value in the area ahead of the ship as the ship is propelled through the water, increasing somewhat as the bow of the ship passes the mine and thereafter increasing progressively until the ship's propeller is above the mine. The acoustic device included in the system of the present invention is adjusted to operate on the strength or intensity of signals received from the ship's propeller corresponding generally to the intensity of signals detected beneath the forward or amidship portion of the vessel, such adjustment being made by a change in the pressure between the contacts 77 and 78 resulting from the rotation of the ring member 81, FIG. 6.

When such a signal is received, the diaphragm 56 vibrates sufficiently to cause the post 57 secured to the diaphragm to oscillate. When this occurs, the contact 77, secured to the balance wheel 76, is alternately moved away from and, by reason of the resilient spring 74, moved into engagement with contact 78 associated with the post 57, thereby alternately opening and closing a circuit comprising the contacts 77 and 78.

In the event a heavy explosion such, for example, as that associated with countermine operations, occurs within the vicinity of the mine, the diaphragm 56 and post 57 vibrate sufficiently to cause the contact 77 to be momentarily moved into engagement with contact 82 secured to the mounting strip 62, thereby closing a circuit comprising the contacts 77 and 82, the resilient spring 74 thereafter restoring the contact 77 to its initial position into engagement with contact 78.

In view of the foregoing, it is apparent that the firing operation of the system is dependent upon the amplitude or intensity of sound signals within a predetermined band of frequencies corresponding approximately to the resonant frequency of the tickler for the reason that the tickler cannot be caused to operate in response to signals of a frequency outside such band notwithstanding that the amplitude of such signals exceeds that required by a particular adjustment of the tickler to set the same in operation.

However, if the amplitude is extremely large, as in the case of signals due to countermine shocks, the tickler is forced to vibrate sufficiently at a frequency other than its resonant frequency to cause a countermine operation of the system. Thus an arrangement is provided which is adapted to respond to certain signals transmitted through the surrounding water and to discriminate against certain other signals which would tend to fire the mine.

FIG. 8 of the drawings shows in diagrammatic form a firing control circuit including the heretofore described sound responsive device, suitable for use in the mine of

FIG. 1. The circuit comprises a pair of cold cathode trigger type tubes 98 and 99, each of the tubes having an anode or plate 101, a cathode 102 and a control grid 103, and a pair of condensers C1 and C2, condenser C1, being normally charged to substantially the potential of the battery BA and condenser C2 being charged to a predetermined fixed potential.

A shipcounter 111, preferably of the type having a plurality of fusible elements adapted to be melted in succession in response to the passage of a plurality of vessels moving in succession past the mine, is operatively connected to the normally charged condenser C1, and is adapted to be operated by the condenser C1, when it discharges. The condenser C2 is connected to the control grid 103 of the firing tube 99 and prevents a rapid increase of potential of the control grid as the acoustic tickler 46 operates sufficiently to disengage the normally closed contacts 77 and 78.

The circuit also comprises an arming clock A suitable for the purpose such, for example, as the mechanism described and claimed in the copending application of James B. Glennon, et al. for Firing Mechanism for a Submarine Mine, Serial No. 395,230, filed May 26, 1941. As is well known in the art to which the invention appertains, the arming clock A is adapted to complete a plurality of circuits in predetermined sequential order when a predetermined period of time has elapsed after the launching of the mine.

The operation of the system of the instant invention will now be described with particular reference to FIG. 8 of the drawings. Let it be assumed that the mine 10 has been launched into a body of water and has come to rest on the bed thereof. Let it further be assumed that the extender mechanism 25 has operated and moved the detonator 26 into operative relation with the booster charge 24.

After an interval of time has elapsed during which a salt washer comprising an element of the clock mechanism A, FIG. 8, is dissolved, a diaphragm 105 comprising another element of the clock mechanism is permitted to move under pressure of the surrounding water and to initiate the operation of a spring wound motor, which motor drives cam 106 of the clock mechanism a predetermined distance. While the cam 106 is rotating, contact spring 107 is moved into engagement with contact spring 108, thereby completing a circuit from the electro-responsive detonator 109 to the ship counter indicated generally by the numeral 111. As the cam 106 continues to rotate, the contact spring 112 is moved into engagement with contact spring 113, after which the cam ceases to rotate. When contact spring 112 engages contact spring 113 a circuit is completed from the positive terminal of battery BA over a conductor 114, contact springs 113 and 112 of the clock A, conductor 115, resistor R1, conductor 116 and thence to the plates 101 of the trigger tubes 98 and 99, thereby applying a plate potential to each one of the tubes of a value controlled by the magnitude of the resistor R1 and the current caused to flow therethrough by the voltage output of battery BA.

A potential is also applied to the control grids 103 of the tubes 98 and 99 when contact spring 112 engages contact springs 113 and 112, conductor 115, resistor R1, the positive terminal of battery BA over conductor 114, contact springs 113 and 112, conductor 115, resistor R1, conductor 116, resistor R4 and thence to the control grid 103 of tube 99; the circuit of the tube 98 continuing from the resistor R4 over conductor 117, contacts 78 and 77, acoustic tickler 46, conductor 118, resistor R6 and thence to the grid 103 of tube 98. The value of the potential applied to the grids 103 of tubes 98 and 99 is controlled by the values of the resistors R1, R2, R3, R4, and R5, the resistors being connected in series across battery BA, to form a voltage divider, and the control grids 103 are connected electrically to the same point on the divider,

thereby causing the voltages applied to the grid of each tube to be substantially equal and to be substantially one third of the voltage applied to the plates 101 of the tubes.

Concurrently with the closure of contacts 112 and 113 of the arming clock A, condenser C1, charges to the output voltage of battery BA minus the potential drops across the resistors R1 and R5, a circuit being closed from the positive terminal of battery BA over conductor 114, contacts 113 and 112 of arming clock A, conductor 115, resistor R1, conductor 116, condenser C1, conductor 119, resistor R5, conductor 121, from whence the circuit is completed to the negative terminal of battery BA. It will be understood that during the charging period of condenser C1, a small value of current flows from the positive terminal of battery BA over conductor 114, contacts 113 and 112 of the arming clock A, conductor 115, resistor R1, conductor 116, resistor R4, conductor 117, condenser C2, conductor 121, from whence the circuit is completed to the negative terminal of battery BA, thereby causing the condenser C2 to become charged to the normal grid potential of the tubes.

When an enemy vessel moves into proximate relation with respect to the acoustic tickler 46, the vibrations caused by the ship's propeller and transmitted through the surrounding water cause the contact 77 of the tickler 46 to be moved away from the contact 78 thereof, as heretofore described. When this occurs, the charge on the condenser C2 is caused to increase by reason of the resistors R2 and R3 being cut from the voltage divider circuit. The condenser C2 obtains this increase in charge over the following circuit; positive terminal of battery BA, conductor 114, contacts 113 and 112 of the arming clock A, conductor 115, resistor R1, conductor 116, resistor R4, conductor 117, condenser C2, conductor 121 and thence to the negative terminal of battery BA, thereby increasing the potential at the point 122, which potential is applied to the grid 103 of the firing tube 99. However, the tube 99 is not fired at this time for the reason that the potential at the point 122 is not sufficient to cause the tube to break down.

As the enemy vessel continues to approach the mine and reaches a point directly over the mine, a sufficient number of vibrations of the contact 77 will have occurred to increase the charge on the condenser C2 and, concurrently therewith, the potential applied to the grid 103 of tube 99, whereby the tube is caused to fire. When this occurs, the normally charged condenser C1 discharges over the following path; positive plate of condenser C1, conductor 116, through the tube 99, conductor 121, the fusible element 123 of the ship counter 111, conductor 119 and thence to the negative plate of condenser C1, thereby melting the element 123 of the shipcounter, and causing the spring contact element 124 associated therewith to move into engagement with the plate contact 125 of the second fusible element 126.

As the firing tube 99 is fired, the voltage at the point 127 in the circuit, which is the voltage applied to the condenser C1, and to the plate 101 of the tube 99, is decreased below that of the main gap sustaining voltage of the tube, by reason of the resistor R5, which is of low value and connected between conductors 119 and 121 thereby extinguishing the tube. Furthermore, when the tube is firing the condenser C2 loses some of its charge over the following path; positive plate of condenser C2, conductor 117, control grid 103 and cathode 102 of tube 99, conductor 121 and thence to the negative plate of condenser C2, thereby reducing the potential of the point 122 in the circuit.

The voltage on the normally charged condenser C1 now starts to build up over its charging circuit and the charge on condenser C2 also builds up over its charging circuit in response to the continuous vibration of contact 77 of the tickler 46. The condenser C2 will reach the firing bias and when the voltage at point 127 increases to approximately two-thirds of the voltage output of bat-

tery BA, the tube 99 again fires, thereby discharging condenser C1. The discharge current of the condenser under these conditions, however, is insufficient to re-operate the shipcounter since the charge on condenser C1 is but two-thirds its normal value. As the condenser discharges, the potential applied to the plate 101 of tube 99 is reduced to a value below that of the main gap sustaining voltage of the tube, thereby extinguishing the tube. This cycle of operations is repeated until the vessel has proceeded a sufficient distance past the mine as to be incapable of causing disengagement of the contacts 77 and 78 of the tickler 46, thereby preventing the potential at 122 from building up to the necessary firing bias for the tube 99. When this occurs, the condenser C1 is again charged to substantially the potential of battery BA and the charge on condenser C2 is restored to its normal potential insufficient to fire the tube 99. The system is now in readiness to respond to the next vessel which passes above or near the mine.

In a similar manner, the next succeeding eight fusible elements are destroyed in response to vibrations detected by the acoustic tickler from the next eight succeeding vessels to pass over the mine. The detonator 109 is now included in the discharge path of condenser C1, since the operation of the last remaining fusible element 134 in the shipcounter 111 will cause the detonator 109 to be fired by the remaining discharge current from the condenser C1.

As the tickler vibrates in response to the passage of the tenth vessel over the mine, the potential at 122 increases to the firing bias of tube 99 and the tube fires. When this occurs, the condenser C1 discharges over the following path; positive plate of condenser C1, conductor 116, plate 101, grid 103 and cathode 102 of tube 99, conductor 121, fusible element 134, conductor 119 and thence to the negative plate of condenser C1, the remaining discharge current from C1 continuing from fusible element 134 over conductor 128, electro-responsive detonating device 109, conductor 129, contacts 108 and 107 of arming clock A, conductor 131, conductor 119 and thence to the negative plate of condenser C1, thereby firing the mine beneath a vulnerable portion of the tenth vessel to pass over the mine.

In the event that a countermine signal is received, contact 77 of the acoustic tickler 46 moves into engagement with contact 82 thereof, whereupon the voltage applied to the plates 101 of the tubes 98 and 99 is also applied to the control grid 103 of the tube 98 through the contacts 77 and 82 of the tickler and conductor 118, thereby causing the tube 98 to fire. When this occurs, the normally charged condenser C1 discharges over the following path; positive plate of condenser C1, conductor 116, plate 101, grid 103 and cathode 102 of tube 98, conductor 132, resistor R2, conductor 119 and thence to the negative plate of condenser C1, thereby sterilizing the system. The tube 98 continues to fire until the condenser C1 has discharged sufficiently to cause the voltage at the point 127 in the circuit, which voltage is applied to the plates 101 of both tubes 98 and 99, to fall below the main gap sustaining voltage of tube 98, thereby extinguishing the tube.

When the tube 98 becomes non-conductive, condenser C1 begins to recharge through resistor R1 to its initial value, sterilization of the circuit continuing until C1 obtains its initial charge. It will be understood at this point that the firing tube 99 is not fired as a countermine signal is received by reason of the time required to raise the voltage of condenser C2 sufficiently to fire the tube. Moreover, when tube 98 is extinguished, the potential applied to the plate 101 of tube 99 decreases concurrently with the decrease in the plate potential of tube 98, thereby further insuring that tube 99 will not fire in response to a countermine signal.

It will be noted that the time constants associated with the RC combination of resistor R1 and condenser C1 and

resistor R2 and condenser C2 are such that the system will normally respond to the passage of a vessel over the mine, substantially independent of the speed with which the vessel moves past the mine. If a vessel is moving rapidly, the short time constants provided allow condenser C2 to charge sufficiently to fire tube 99 and discharge condenser C1 through the shipcounter. When tube 99 is extinguished, the charges on both condensers rise concurrently, the interval of time required being relatively short, thereby rapidly adjusting the system to be in readiness to respond to the next succeeding vessel passing over the mine.

If a vessel moves slowly past the mine, the condenser C2 obtains sufficient charge to cause tube 99 to fire as the vessel reaches a point directly over the mine, thereby causing C1 to discharge through the shipcounter. As the vessel slowly moves away from the mine, the charges on condensers C1 and C2 rise concurrently, the condenser C2 being adapted to discharge and charge repeatedly without additionally operating the shipcounter if the sound signals received by the tickler are of a predetermined character, adapted to cause condenser C2 to obtain a charge sufficient to fire tube 99. An arrangement is thus provided whereby the system is adapted to operate satisfactorily in response to the passage of a wide variety of vessels over the mine at various speeds.

It will be understood that the sensitivity of the system may be varied in two ways. Rotation of the ring member 81 varies the pressure between the normally closed contacts 77 and 78 and thereby the response of the tickler 46 to the intensity of vibrations or pulsations transmitted through the surrounding water is increased or decreased in accordance with the direction of rotation of the member 81. Moreover, by changing the value of capacitance of the condenser C2, the interval of time required to increase the voltage applied to the grid 103 of tube 99 sufficiently to fire the tube may be varied in accordance with an increase or decrease in the capacity of C2.

In a specific circuit, the following values of circuit constants have been found to be satisfactory. The voltage output of battery BA is in the order of 135 volts; therefore, the voltage at the point 127 in the circuit is 135 volts minus the potential drop across the 0.5 megohm resistor R1. Substantially, however, the voltage applied to the plates 101 of the trigger tubes 98 and 99 is 135 volts, a voltage equal to or greater than the main gap sustaining voltage for the type of cold cathode tube employed herein. In accordance with the values of the resistors R1—R5 which form a voltage divider circuit, the initial potential existing at the points 122 and 133 in the circuit is one-third that of the plate voltage, hence 42 volts, this voltage being substantially less than the firing bias of these tubes. The grids 103 of both the tubes 98 and 99 are connected to the same point in the voltage divider circuits, which point embraces the resistor R3, 1 megohm; R2, 5 ohms and R5, also 5 ohms. The remaining resistors R1, 0.5 megohm and R4, 2 megohms, constitute approximately two-thirds the total resistance in the divided circuit. Values of capacity of the condensers C1 and C2 which have produced satisfactory time intervals are 125 microfarads and 0.5 microfarad, respectively. The resistor R6, 10,000 ohms, is provided in the grid circuit of tube 98 in order to protect the tube from high currents while the tube is firing. Thus, substantially no current flows through resistor R6 whereby a negligible voltage drop appears thereacross and the voltages at the grids of the tubes 98 and 99 normally are substantially equal.

Briefly stated in summary, the instant invention contemplates a new and improved acoustically controlled mine firing system, wherein an acoustic tickler is adapted to selectively control the operation of a pair of electron discharge devices, which devices in turn selectively control the discharge path of an electrolytic condenser in accordance with the character of signals detected by the tickler.

While the invention has been described with particular

reference to an example thereof which gives satisfactory results, it will be readily apparent to those skilled in the art to which the invention appertains, after understanding the invention herein described, that further embodiments, modifications and changes of the invention may be made without departing from the spirit and scope thereof, as defined by the claims appended hereto.

The invention herein described and claimed may be manufactured and used by or for the Government of the United States of America without payment of any royalties thereon or therefor.

What is claimed as new and desired to be secured by Letters Patent of the United States is:

1. In an acoustically controlled marine mine adapted to be fired in response to sound signals received from an approaching vessel, a sound responsive device adapted to be set into operation as the vessel enters the threshold of sensitivity of the mine, a source of electrical energy, a discharge path for said source of energy, detonating means included in said discharge path and adapted to be fired as energy flows in the path, an electrical energy storage device, means including said sound responsive device for causing energy from said source to be stored periodically in said energy storage device as the sound responsive device operates and time measuring means controlled by said sound responsive device and including said energy storage device for causing energy to flow through said path when a predetermined period of time has been measured by the time measuring means in response to continuous operation of the sound responsive device.

2. In a mine of the character disclosed, in combination, a sterilizing circuit therefor, a firing circuit therefor, a normally charged condenser connected to both said sterilizing circuit and said firing circuit, a first discharge tube included in said sterilizing circuit and adapted to cause said condenser to discharge therethrough when the tube is fired, a second discharge tube included in said firing circuit and adapted to cause said condenser to discharge therethrough as the second tube is fired, and electric contact actuating apparatus comprising a plurality of contacts adapted to be actuated by sound waves and to control the firing of said first and second discharge tubes selectively in accordance with the character of the sound waves.

3. In an acoustic mine firing control system, a normally inactive mine firing circuit, a sound responsive device comprising a pair of contacts adapted to be vibrated in response to sound signals transmitted through an elastic medium, a source of electric power connected to said contacts, a condenser connected to said contacts and adapted to be charged by said source of power when the contacts vibrate, circuit means including said contacts and said condenser for producing a firing actuation of said mine firing circuit when the charge on the condenser reaches a predetermined value.

4. In a mine of the character disclosed, in combination, electric contact actuating apparatus comprising a plurality of contacts adapted to be actuated by sound waves, a normally inactive mine firing circuit, a condenser included in said circuit, a source of power, circuit means including a first pair of contacts included in said plurality of contacts and adapted to connect said condenser to said source of power intermittently in a manner to charge the condenser therefrom above a predetermined initial value as the contacts are actuated in response to sound waves of a predetermined character, circuit means controlled by the charge on said condenser and adapted to activate said firing circuit when the charge on the condenser reaches a second predetermined value, a second pair of contacts included in said plurality of contacts and adapted to be actuated by sound waves of a different character, and means controlled by said second pair of contacts and adapted to prevent an activation of said firing circuit when signals of a different character are received.

5. In a mine of the character disclosed, a sound re-

sponsive device adapted to be set into operation by sound signals transmitted through the surrounding water, first and second pairs of contacts on said sound responsive device, said first pair of contacts being adapted to vibrate when sound signals of a predetermined character are received by the sound responsive device, a source of electrical energy connected to said first and second pairs of contacts, a first condenser connected to said first pair of contacts and adapted to become charged from said source as the contacts vibrate, a normally charged condenser, electro-responsive detonating means adapted to be operated by the discharge current from said normally charged condenser, a first electron device having an anode thereof connected to said normally charged condenser and a control element thereof connected to said first condenser, said electron device being adapted to fire as the first condenser becomes charged to a predetermined value and to cause said normally charged condenser to discharge through said detonating means as the electron device is fired, said second pair of contacts being adapted to be operated when sound signals of a different character are received by the sound responsive device, and a second electron device having the anode thereof connected to said normally charged condenser and a control element thereof connected to said second pair of contacts, said second electron device being adapted to cause the normally charged condenser to discharge through the second electron device when the second pair of contacts are operated.

6. In a mine of the character disclosed, a source of power, a condenser connected to said source of power and normally charged to the potential thereof, a discharge path for said condenser, an electro-responsive shipcounting device included in said path, and means including a sound responsive device and controlled by sound signals transmitted through an elastic medium for causing said condenser to discharge through said path when a predetermined interval of time has elapsed after the sound responsive device responds to the first of said signals, thereby to operate said shipcounting device.

7. In an acoustically controlled marine mine, a normally charged condenser, a mine firing circuit including an electro-responsive detonating means and comprising a first discharge path for said condenser whereby said detonating means is operated as the condenser discharges through said path, a second discharge path for said condenser adapted to sterilize the mine for a predetermined period of time when the condenser is discharged therethrough, a sound responsive device adapted to be set into operation when sound signals are received thereby, circuit means including a plurality of contacts controlled by said sound responsive device, and means controlled by said contacts and adapted to cause said condenser to discharge through said first and second paths selectively in accordance with the character of signals received by the sound responsive device.

8. In an acoustically controlled marine mine, a sound responsive device adapted to be set into operation in response to signals transmitted through the surrounding water, a source of energy, a plurality of discharge paths for said source of energy, detonating means included in one of said paths and adapted to fire the mine as energy flows in said one of the discharge paths, time measuring means controlled by said sound responsive device and adapted to cause energy to flow in said one of said discharge paths when a predetermined period of time has been measured thereby in response to the continuous operation of the sound responsive device as a signal of predetermined character is received by the device, and means controlled by the sound responsive device and adapted to cause energy to flow in another of said discharge paths for a predetermined period of time when signals of a different character are received by the device, thereby sterilizing the mine for said predetermined period of time.

9. In a mine of the character disclosed, the combination of a source of power, a condenser, means for charging said condenser to substantially the potential of said source of power, a discharge path for said condenser, an electron device included in said discharge path and adapted to cause said condenser to discharge as the electron device fires, counting means also arranged within said discharge path and adapted to be operated when said condenser discharges, a control element for said electron device, time measuring means operatively connected to said control element and adapted to fire the electron device when a predetermined period of time has been measured by the time measuring means, a sound responsive device for controlling the operation of said time measuring means in response to sound signals received from a vessel by the sound responsive device, and means for causing said condenser to charge and discharge repeatedly after said counting means has been operated without additionally operating the counting means during the travel of the vessel past the mine.

10. In a mine of the character disclosed, a vibration responsive device adapted to be set into operation by sound waves or pulses of a predetermined character, an electron device, a normally charged condenser connected to said electron device and adapted to be discharged thereby when the electron device is fired, counting means adapted to be operated by the discharge current from said normally charged condenser, a control element for said electron device, a second condenser connected to said control element and adapted to fire said electron device when the second condenser is charged to a predetermined value, means including said vibration responsive device for charging said second condenser in response to continuous operation of the vibration responsive device, detonating means, and means included within said counting means for operatively connecting the detonating means to said normally charged condenser when the counting means has been operated a predetermined number of times whereby the detonator means is fired by the discharge current of the normally charged condenser during the next succeeding discharge thereof.

11. A sterilizing circuit for an acoustic mine firing control circuit comprising a source of power, a normally charged condenser included in both said circuits, a discharge path for said condenser, a trigger tube included in

said path and adapted to discharge the condenser therethrough when the tube fires, said tube being extinguished as the condenser is discharged, a path including said source of power for gradually charging the condenser to the normal charge thereof, a pair of normally open contacts for controlling the firing of said tube, and means responsive to sound signals of a predetermined character for closing said pair of contacts.

12. In a vibrationally controlled underwater mine, a source of electrical power, a condenser, means for normally charging said condenser to substantially the potential of said source of power, two discharge circuits for said condenser, an electro-responsive detonating means included in one of said discharge circuits for firing the mine, a pair of electron discharge tubes in circuit with said condenser and adapted to control the discharge of said condenser through said discharge circuits selectively in accordance with the firing of the tubes, a vibration responsive device adapted to be set into operation by vibrations transmitted through the surrounding water, and circuit means including a plurality of contacts controlled by said vibration responsive device for firing said electron discharge tubes selectively in accordance with the character of vibrations received by the vibration responsive device.

13. In a mine of the character disclosed, in combination, a vibration responsive device adapted to be set into operation as vibrations or pulsations are transmitted through the surrounding water, a source of electrical power, a pair of discharge tubes connected to said source of power, a normally charged condenser connected to the anodes of said discharge tubes and adapted to be discharged through the tubes when the tubes are fired, and circuit means including a plurality of contacts controlled by said vibration responsive means for firing said discharge tubes selectively in accordance with the character of the vibrations received by the vibration responsive device.
